UNITED STATES PATENT OFFICE.

HANS THOMA, OF MUNICH, GERMANY.

ROTARY PUMP AND MOTOR.

Application filed March 26, 1924, Serial No. 702,103, and in Germany November 25, 1922.

This invention relates to rotary motors and pumps of the kind in which a rotor having radial cylinders therein, with pistons in the cylinders, rotates in a drum which is 5 eccentric in relation thereto, the pistons bearing against the inner surface of the drum, and liquid being supplied to, and discharged from, the said cylinders by means of ducts and ports in a non-rotating trunnion upon 10 which the rotor rotates.

One object of my invention is to reduce the lateral thrust on the trunnion, due to the pressure of the liquid, generally oil, and another object is to provide improved means 15 for regulating the speed of the motor in apparatus wherein a pump and a motor, both of the kind referred to, are so combined that liquid propelled by the pump is used for driving the motor.

20 The invention is illustrated in the accompanying drawing in which,

Fig. 1 is a horizontal section of a pump or motor, and

Fig. 2 a vertical section thereof in two 25 different planes.

Fig. 3 is a cross section of the rotor trunnion, to a larger scale, and

Figs. 4 and 5 are a side view and a plan 30 view of the said trunnion respectively.

Fig. 6 shows diagrammatically the combination of a pump and motor as hereinbefore referred to, and

Fig. 7 is a horizontal section of part of 35 this apparatus.

Fig. 8 is a development of the surface of a cam forming part of the mechanism shown in Fig. 7.

Referring first to Figs. 1 and 2, the casing 1 has fixed therein a trunnion 2, round which 40 rotates the rotor 3, one wall of the casing having a bearing for one end of the trunnion, the other end of which is unsupported. In the rotor 3 are the radial cylinders 4, with pistons 5 therein. The outer end of each 45 piston has a cross-head 6, whose diameter exceeds the diameter of the piston. This crosshead is traversed by a pin 7 having at its projecting ends gudgeons for rollers 8, which run on the inner circumferential surface of a drum 9. The latter is rotatable on ball bearings 12 mounted on a holder 10, which is adjustable diametrically of the casing 1, between guides 10^a, the adjustment being effected by means of a screw spindle 10^b.

50 This adjustment enables the eccentricity of the drum 9, and consequently the stroke of

the pistons 5, to be regulated; it also enables the direction of discharge of the pump or of rotation of the motor to be reversed.

The supply and discharge of the driving 60 or driven fluid, generally oil, takes place through conduits 13 and 14 in the trunnion 2 and radial ports 15 and 16 in the rotor, opening into the cylinders. In order to provide for lubrication of the rollers 8 there 65 are ducts 17 and 18 in the pistons and cross-heads. In order to relieve the central pivot or trunnion 2 to some extent of lateral thrust, there are two annular grooves 19 in the said trunnion near the ports 15 and 16. These 70 grooves limit, to a defined length of the trunnion, the spreading of oil along the surface of the trunnion, and become filled with oil which has been forced along the surface of the trunnion from one or other of the 75 ports, and the grooves thus constitute circular channels filled with oil, which transmit fluid pressure from one side of the trunnion to the other and to some extent 80 balance the thrust. Additional relief is afforded by branch channels 20, forming loops of the channels 19 and bounding rectangular surface portions 21 of the trunnion on the suction side.

The rotor is connected with the driving 85 or driven shaft 22 by means of a coupling plate 23 having dogs 23^a which engage recesses in the rotor, and having also a dog 23^b which engages a slot in the end of the shaft. The dogs 23^a do not entirely fill the 90 recesses wherein they lie, and the plate does not entirely fill the space between the rotor and the shaft, so that a slight amount of axial and rotational play is allowed.

Figs. 6 and 7 show an example of apparatus in which a rotary motor and a rotary pump, both constructed in accordance with my invention, are combined, 34 being the pump, which has a driving pulley 35, and 36 being the motor, which may be used, for example, for driving a machine tool or lathe. An oil container 37 is connected to the pump and the motor. The pump 34 sucks oil from said oil-container, whilst the motor 36 delivers the spent oil to the container.

100 In order to prevent over-heating of the oil the oil container is of substantial size in relation to the capacity of the pump and motor, and it is placed below the motor and pump in the foot of the machine frame, where 105 massive metal parts are available for conducting heat.

In the case of a lathe, it is important to be able to obtain definite speeds of the driven shaft by adjusting the gear. With the apparatus shown in Figs. 6 and 7 regulation 5 can be effected, up to the point at which the pump attains its maximum output, by regulating the eccentricity of the drum in the pump, as described with reference to Figs. 1 and 2. The additional regulation, for obtaining further increase of speed, can be effected by decreasing the eccentricity of the drum in the motor, this being done without altering the maximum eccentricity given to the pump drum. To this end there is 10 mounted on an axle at one side of the pump and motor, a cam cylinder 86 (Fig. 7 or 8) having at its circumference a channel 87. This channel is not continuous, and consists of a straight portion with curved portion at 15 each end. Within this channel run two rollers 88, 89, mounted at the ends of arms 90 connected respectively to the adjustable holders of the drums in the pump and motor. The cam cylinder can be rotated by means of 20 a hand wheel 93 and suitable gearing. By rotation of the cam while the roller 88 is in one of the curved portions of the channel 87 the drum in the pump is moved, and while this movement is taking place the roller 89 25 is in the straight part of the channel, so that the drum in the motor is not moved. When the pump drum has been moved to its position of maximum eccentricity, continued rotation of the cam results in the roller 89 30 engaging the other curved portion of the channel 87, whereas the roller 88 engages the straight part of the channel. Consequently the motor drum is moved transversely of the motor axis, whereas the pump drum remains 35 stationary. Fixed to the cam axle is a pointer 91, which works on a dial having a scale marked thereon, the scale indicating the rates of revolution of the motor obtainable by setting the cam in the positions indicated by the pointer.

Claims:

1. A hydraulic variable speed gear con-

sisting of a pump and a motor driven by the pump discharge, each comprising a drum, a rotor disposed eccentrically within the drum 50 and having radial cylinders, said drum being movable to different positions of eccentricity with relation to said rotor, pistons in said cylinders, crossheads fixed to said pistons, rollers mounted on said crossheads in contact 55 with the inner circumference of the drum, a bearing, and a trunnion upon which said rotor is rotatable, said trunnion having one of its ends fixed within said bearing, the other end being unsupported, and said trunnion having at opposite sides thereof ports for the flow of liquid to and from said cylinders, and having also on each side of said ports an annular groove for limiting the spreading of liquid from the ports to a defined length of the trunnion, and regulating mechanism whose actuation in one direction first causes movement of the pump drum to a position of maximum eccentricity in relation to the pump rotor, the motor having 70 its maximum capacity during that movement, and then causes movement of the motor drum reducing its eccentricity, without moving the pump drum.

2. A hydraulic variable speed gear, according to claim 1, in which the regulating mechanism comprises adjustable holders for the pump drum and the motor drum respectively, movable for varying the eccentricity of said drums, a cam having a groove which 80 has a straight portion and curved portions in continuation of said straight portion, and two rollers engaged with said groove, mounted on said adjustable holders respectively, whereby rotation of said cam imparts 85 movement to said holders when the respective rollers are in the curved portions of said groove, said rollers and said cam being so positioned that when in the course of rotation of said cam either of the rollers is in 90 the straight portion of said groove the other roller is in one of the curved portions of said groove.

HANS THOMA.
